UNITED STATES PATENT OFFICE.

BENJAMIN ANDREWS, OF HOUSTON, TEXAS.

METHOD OF SULPHUR MINING.

Application filed June 7, 1927. Serial No. 197,203.

My invention relates to sulphur mining, but more particularly to the mining of subterranean deposits of sulphur by means of hot water, which, when pumped into the sulphur bearing stratum through deep wells, act as a medium to fuse the sulphur so that it might be raised to the surface in its liquid state.

The underground deposits of sulphur, occurring particularly in the salt domes found along the coast of the Gulf of Mexico, are located beneath waterbearing sands. The sulphur occurs in a water flooded porous lime and gypsum rock which becomes connected with the water sands above, through cavings incidental to the application of the mining process. As a result it is found that the heavier cold water above flows down into the sulphur cavity displacing the lighter hot water that has been discharged into the formation through the wells forcing this heat bearing water out of the sulphur cavity into the overlying barren sands, thereby causing the loss of this valuable vehicle and vitiating entirely its sulphur melting effect, and making the heating and fusing of the sulphur difficult and expensive due to the waste of the predominant proportion of the thermal units carried off by this water escaping into the upper sands.

An object of my invention is to prevent the overlying cold water from flowing down into the sulphur bearing horizon and displacing the hot waters therein, and thus to place the removal of the mine waters entirely under control of the operator so that the heating fluid may be applied to specific zones where unmelted sulphur deposits are known to exist.

Reference is made to the drawing herewith in which a vertical section of a sulphur mine is shown in such manner as to illustrate the carrying out of my invention.

The drawing is intended to show the various formations such as ordinarily occur in a "mound" where sulphur is found. The sulphur, indicated at 1, is ordinarily present in a porous gypsum rock 2 lying above a stratum of salt 3. A stratum of water bearing sand 4 is usually present closely above the sulphur deposits, but separated from it by a bed of clay or shale 13.

A sulphur well may be drilled down through the different strata to the sulphur formation. Such a well is shown somewhat diagrammatically at 5. The numeral 6

designates the casing, which at its upper end is provided with a casing head 7 through which the heated liquid may be pumped. A sulphur outlet pipe 8 extends through said casing head to the sulphur stratum. It forms a fluid-tight fit through the casing head, as shown. An air discharge pipe 9 of small diameter extends downwardly inside the sulphur pipe. Said air pipe discharges the air into the sulphur pipe at a point spaced upwardly somewhat above the bottom and serves to aerate and "lift" the sulphur so that it may be raised to the surface by the fluid pressure in the well. The hot water ordinarily pumped into the mine is fresh water which has been heated to a temperature above the fusing point of sulphur. Such water, as well as the mine water to which it has imparted some heat, because of its high temperature, is necessarily of lighter specific gravity than the free cold water in the water bearing sands above the mine. For this reason, the cold waters above tend to descend in convectional currents downwardly into the sulphur bearing formation pushing away the hot injected water with any proportion of the mine water present that might have absorbed any of its heat and all of this warm water is forced into the overlying sands. In order to secure the best effect and bring any of the heated water in contact with the sulphur in the formation, it becomes necessary to pump immense quantities of hot water into the mine and depend more or less on accident for results, as the supply of cold water above is practically inexhaustible. Needless to say the present system of mining sulphur is thermally extremely inefficient; probably the most successful operations do not secure a thermal efficiency of 5% of perfect.

To overcome this difficulty, I contemplate pumping into the sulphur mine, through the system of pipes, such as are now employed for delivering the hot water therein, a large quantity of water which I make of heavy specific gravity through the mixing therewith of salt. This cold heavy water is pumped into the mine until it displaces the larger portion of the cold water already present. The said cold water originally in the mine is thereby forced upwardly away from the sulphur cavities into the water bearing sands above. After the mine has been flooded with the heavier liquid there will be no tendency for the light colder

waters from above to run down into and cool the mine.

I next drill an additional well, such as is shown in the drawing at 10. This well is 5 preferably drilled to a point lower in the formation than the bottom of the well shown at 5. It has an outer casing 11 and an air inlet pipe 12. This well will act as a so-called bleed well to take water from the 10 underground formation, the quantity of which will be regulated at the will of the operator according to its density and temperature. The process from then on is the same as is usual in the operating of the 15 sulphur mine, but I prefer to use heavier salt laden hot water, as is described in my co-pending application No. 28,020, filed May 4th, 1925.

The action of the process thus to be carried out will be about as follows:

The heating medium will be discharged, or applied, adjacent the sulphur stratum through well 5, and will at first rise upwardly toward the upper surface of the sulphur stratum heating and carrying with it some of the cold water already present. It will then serve to heat the upper portion of the mine and this heat will be gradually extended downwardly as the cold water is removed from the bleed well 10. The water in the formation will be of heavier gravity than that of the cold water in the sands and this cold water will have no tendency to run down and displace the hot mine water. 25 Thus the hot water pumped into the sulphur formation will be confined thereto and no further addition of cold water to the sulphur stratum will tend to occur. The final result will be that the total sulphur bearing stratum 30 will be filled with hot water and the cold heavy water first pumped into the mine will be gradually drawn off through the bleed well 10.

In this way, the hot water may be efficiently brought into contact with the sulphur in the formation which will all be fused, and will run by gravity toward the lower end of the mine 5 where it may be raised to the surface and thus saved. It will be 45 obvious that this method will be much more economical than the present method and will also make it possible to remove more effectively the greater quantity of sulphur from the sulphur producing stratum. The further 50 objects and advantages of the invention will be apparent to those skilled in the art. What

I claim as new and desire to protect by Letters Patent is:

1. In the mining of sulphur from underground deposits by means of the hot water process, the improvement comprising first preparing the same for operation by displacing part or all of the natural mine waters with a liquid of heavy specific gravity, then applying to the same the heating agent and controlling the zones of application of the heat by removing the mine waters through suitably located outlets. 60

2. In the mining of sulphur from underground deposits by means of the hot water process, the improvement comprising first displacing the natural mine waters with a liquid of comparatively heavy specific gravity, then forcing into the mine a liquid of heavy specific gravity heated to a point 70 above the fusing point of sulphur, and simultaneously removing the heavy mine waters through suitably located outlets. 75

3. In the mining of sulphur from underground deposits by means of the hot water process, the improvement comprising first displacing the natural waters in the formation with a liquid of comparatively heavy specific gravity, then applying a suitable heating agent and simultaneously removing the heavy liquid first pumped into the well 80 through suitably located outlets. 85

4. In the mining of sulphur from underground deposits by means of the hot water process, the improvement comprising first displacing the natural waters present in the mine with a liquid of comparatively heavy specific gravity, then introducing a hot liquid whose specific gravity has been raised 90 above that of the water originally present 95 in the mine, and gradually eliminating the heavy water and thereby controlling the zones of application of the hot water.

5. In the mining of sulphur from underground deposits having cold water present therein, the method comprising first driving from the formation the free cold water already present and substituting therefor a liquid of comparatively heavy specific gravity, then delivering into the mine hot water 100 of a specific gravity heavier than the original cold water in the mine, and at the same time drawing off through an adjacent well the heavy cold water first pumped into the mine. 105

In testimony whereof I hereunto affix my signature this 1st day of June, A. D. 1927.

BENJAMIN ANDREWS.
